TRAFFIC SIGNAL

Frank W. Griswold, Minneapolis, Minn., assignor,
by mesne assignments, to Griswold Signal Company, a corporation

Application September 18, 1926, Serial No. 136,285
Renewed February 6, 1931

6 Claims. (Cl. 177—327)

This invention relates to a traffic signal such as now used at the intersections of two thoroughfares such as intersecting streets, railways, or the intersection of a railway and a roadway or street. 5 If one signal is to be used at such an intersection, the preferable place for the same is at the center of the intersection where it can be seen by all vehicles and also be plainly seen by pedestrians crossing the thoroughfares. If the signal is not 10 to endanger traffic, it must be so constructed that when a vehicle collides therewith the vehicle and signal will not be damaged. If the signal is to be used at modern city street intersections, it must also be of such a size that it can be disposed between the street car tracks.

One form of traffic signal which has been very successfully used at such intersections is that shown in applicant's prior Patent No. 1,760,270, granted May 27, 1930. With such a signal it has 20 been found that at certain times it is quite difficult to see the illuminated sides of the signal, as when the sun is shining on the signal. If the wiring circuits for the signal become damaged, both pairs of characters at one side of the signal might be illuminated, thus confusing the 25 vehicle operators.

It is an object of this invention, therefore, to provide a signal which is positively non-glare in operation, one in which both the "Stop" and "Go" signals cannot be simultaneously displayed for one street, and one which can be easily, inexpensively and efficiently operated.

It is another object of the invention to provide a traffic signal so mounted in the street intersection 35 that it can be swung down substantially into contact with the street in any direction and having a rotating member therein with characters thereon for simultaneously directing traffic to proceed on one street and to stop on another, together with means for periodically partially rotating said member to alternately display the characters at adjacent sides of said signal.

It is another object of the invention to provide a traffic signal comprising a standard mounted to 45 be swung down substantially into contact with the surrounding surface and to be automatically returned to normal position, which standard has a movable member therein having characters thereon for simultaneously directing traffic to proceed on one thoroughfare and to stop on another and 50 also has a motor therein for periodically moving said member alternately to display said characters at adjacent sides of said standard.

It is still another object of the invention to 55 provide a traffic signal comprising a standard

having mounted therein a revoluble member having characters at opposite sides thereof adapted simultaneously to be displayed to direct traffic to proceed on one thoroughfare and stop on another, a driving means in said standard for periodically partially turning said member and a connection between said driving means and member including a slipping clutch.

It is still another object of the invention to provide such a signal as set forth in the preceding paragraph in which a resilient means is also disposed between said driving means and revoluble member.

It is still further an object of the invention to provide a traffic signal comprising a standard having mounted therein a revoluble member having characters on the sides thereof adapted simultaneously to be displayed to direct traffic to proceed on one thoroughfare and to stop on another, with means carried by said standard for illuminating said characters, and means for periodically partially rotating said member.

It is a further object of the invention to provide a traffic signal adapted to be placed at the intersection of two streets, comprising a narrow standard having a rotatable member therein with characters at the sides thereof adapted to be displayed simultaneously to direct traffic to proceed on one of said streets and to stop traffic on the other, with means for periodically partially rotating said member alternately to display said characters at adjacent sides of said standard, said standard being quite narrow, so that the same can be disposed between adjacent street car tracks on a city street.

These and other objects and advantages of the invention will be fully set forth in the following description made in connection with the accompanying drawings, in which like reference characters refer to similar parts throughout the several views and in which:

Fig. 1 is a view partly in side elevation of the signal and partly in vertical section;

Fig. 2 is a view in central vertical section of a portion of the signal;

Fig. 3 is a view in central vertical section of another and upper part of the signal;

Fig. 4 is a horizontal section taken on line 4—4 of Fig. 2, as indicated by the arrows;

Fig. 5 is a view partly in side elevation and 50 partly in vertical section of the clutch used;

Fig. 6 is a view in side elevation of the spring structure used;

Fig. 7 is a view in horizontal section taken on line 7—7 of Fig. 6 as indicated by the arrows;

Fig. 8 is a horizontal section taken on line 8—8 of Fig. 9, Figs. 4 and 8 being on an enlarged scale;

Fig. 9 is a view in side elevation of a partial assembly of the signal;

Fig. 10 is a view in side elevation as seen from the right of Fig. 9, some parts being broken away and others shown in vertical section;

Fig. 11 is a bottom plan view of the clutch shown in Fig. 5, certain parts being broken away;

Fig. 12 is a view in horizontal section taken on line 12—12 of Fig. 3, as indicated by the arrows;

Fig. 13 is a top plan view of the parts shown in Figs. 9 and 10;

Fig. 14 is a bottom plan view of said parts;

Fig. 15 is a diagrammatic view showing connections of the flasher to the motor and its coils and to a source of power, the view also showing the connections for the lamps; and

Figs. 16 and 17 are detail views of features of Fig. 15.

Referring to the drawings, a traffic signal is shown, adapted to be disposed in the thoroughfares, preferably adjacent the center of the intersection of two or more thoroughfares, the material of said thoroughfares being indicated at 20 having a surface 20a which would be the surface of the street when the device is used at a street intersection. A casing 21 illustrated as cylindrical in form is disposed in the material 20 and a plurality of circumferentially arranged brackets 22 are secured to the inner sides of said casing. Said brackets have adjustably mounted thereon the auxiliary brackets 23 having upwardly projecting plates 23a extending radially of casing 21 and having curved surfaces 23b which form the supporting members for a spherical member or ball 24 forming the base of the signal standard. A cable 25 of special construction extends through a boss 24a formed in the ball 24 and through an opening therein, this cable being anchored to said boss by a clamp 25a secured thereto. The cable 25 is surrounded some distance below the ball by an apertured plate 26 to which are secured a plurality of radially extending strong tensile coiled springs 27 anchored at their outer ends to hooks 28a secured in the wall of casing 21. Cable 25 at its lower end has secured thereto a clamp 28 which is anchored by a hook 29 to a plate 30. The plate 30 has connected thereto the upper ends of a plurality of strong tensile springs 31 secured at their lower ends to another plate 32 which is securely anchored by a hook 33 to a member disposed in the bottom of the casing 21 (not shown). While the cable 25 might be of various constructions, in the embodiment of the invention illustrated, and in practice, a special cable of the well known Roebling type is used, having a central passage therethrough. This passage is utilized as a conduit to carry the electrical conductors 34 which have some slack below the lower end of the cable and extend through a conduit 35 communicating with the side of the casing 21, said conduit and conductors passing to a timing mechanism 36. The specific form of timing mechanism used forms no part of the present invention, and any suitable well known form of standard timing mechanism may be used. The casing 21 is provided with a cover 37 extending from the outer side thereof to substantially the sides of the ball 24.

The ball 24 has an upwardly extending flange 24b to which is secured a standard 40. While

this standard may be variously made, in the embodiment of the invention illustrated and in one form which has been found very suitable in practice, the same is made of pressed steel plates 40a, (see Fig. 12), having their corners bent or curved substantially at right angles and suitably nested and secured together in any suitable manner as by bolts or spot welding. Bolts 24c extend through the lower end of these plates through the holes 40d securing the standard to the flange 24b of the ball 24. To column 40 has secured thereto at its top portion a member 41 to which is bolted, by the bolts 42, a cap member 43 having a pointed top and sides which substantially align with the sides of said standard and are provided with openings 43a at the four sides of said standard. Said standard also has elongated openings 40b in each of the four sides thereof adjacent its upper end and also has smaller openings 40c through the four sides thereof some distance below the openings 40b. Secured in said standard a short distance above the ball 24 is a motor 44. This motor in practice has been of the electrical type and comprises a simple reversible motor and one which can have the current thereon at all times and one which can be held from rotation with the current thereon. An armature shaft 44a of the motor extends upwardly and has a half clutch 45 secured thereto meshing with the half clutch 46 secured to the lower end of a shaft 47 which extends centrally upward through the standard 40 and has another half clutch 48 secured to its upper end. The half clutch 48 engages a similar half clutch 49 which is of cylindrical shape and is secured to a friction plate 50 by the rivets 49a extending therethrough and through said plate and having convex heads. A friction plate 51 shown as square or rectangular in form is disposed at each side of the plate 50 which is illustrated as circular in shape, which friction plates may be made of friction fiber or sheet packing material. The lower plate 51 has a metal plate 52 therebelow having a central opening surrounding the member 49 and the upper plate 51 has a metal member 53 surmounting the same which is shown as of a shape similar to plate 51. The plates 51, 52 and 53 are traversed by the headed and nutted bolts 54 having the coiled compression springs 55 thereon between plates 52 and the nuts 56 thereon, one of which nuts forms a jamb nut. It will be noted from Fig. 11 that the bolts 54 pass outside of the plate 50. The plate 53 is secured by the rivets 57 to a cylindrical member 58, said rivets having countersunk heads in said plate and member. The member 58 is secured by set screw 59 to a short stud or shaft 60 extending upwardly from said member and having an upper portion journaled in a bracket 61 secured within the sides of the standard 40. Between members 61 and 58 is disposed a yoke 62 substantially of U-shape and having disk portions at its top and bottom having therethrough apertures with parallel sides adapted to fit a flattened section 60a of the stud 60 which is disposed between members 61 and 58 so that said yoke is non-rotatable relatively to said stud. A pair of collars 63 surround the stud 60 between the ends of the yoke 62, which collars have cylindrical holes therethrough. A coiled torsion spring 64 surrounds collar 63 and is also disposed between the end portions of yoke 62. The ends 64a of the wire or rod forming the spring 64 extend at each side respectively of the vertical member 62a of the yoke 62 and also extend at each side respectively of the pin 61a which is secured in and

depends from the member 61. The stud 60 has a collar or disk portion 60b at the upper portion thereof, from which extends upwardly a short portion 60d which is securely fastened to a small pinion 65. The pinion 65 meshes at opposite sides thereof with planetary gears 66 carried by a bar or block 67 extending thereacross and across the top of gear 65. The gears 66 are mounted on bar 67 by the headed and nutted bolts 68 which have enlarged portions on which the gears 66 are journaled. The gears 66 in turn mesh with the orbit gear 69 held between the member 61 and an upper member 70 also secured to the column 40 by the screws 11. The bar 67 has a shaft 68a extending upwardly centrally thereof journaled in ball bearings 72 mounted in the member 70 and held in place by the collar 73 bolted to member 70, which bearings are spaced by the collar 74. The upper end of shaft 68a has keyed thereto the members 75 to which is non-rotatably secured a member or shell 76. The shaft 68a has a nut 77 at its upper end engaging the top of member 75 and the member 76 has a plurality of circumferentially spaced pins 78 secured thereto in adapted to seat in corresponding holes formed in member 75. The member 70 has bosses 78a projecting inwardly at right angles to each other and in which are secured headed bolts 70b having jamb nuts 70c for holding the same in place, which bolts form stop means adapted to be engaged by the bar 67 when the same is rotated. A washer of felt or similar material 79 is disposed between the upper end of member 70 and the lower end of member 75 and adapted to exclude dust or dirt from the bearing 72. The member 76 forms the bottom member of the unit shown in Figs. 9 and 10. This unit is, as shown in Figs. 13 and 14, substantially square in horizontal cross section and has a ring 80 at its upper end having a squared portion 80a at its lower side. Plates 81 extend between the members 76 and 80, being secured to the sides of members 76 and the portion 80a by the small headed screws 82. The edges of the plates 81 are, as shown, bent substantially at an angle of 45° and overlap at the corners of members 76 and 80 which are also formed at a similar angle. Reinforcing corner plates 81b are disposed at the inner sides of said unit and secured as by spot-welding to plates 81. The plates 81 at opposite sides of the said unit have characters or letters 86 cut therefrom in stencil form, adapted to direct traffic to stop or halt on a thoroughfare, and in the embodiment of the invention illustrated, these characters are shown as the letters "Stop". The plates 81 at their inner sides have secured thereto transparent colored panes 83 made of glass, celluloid, or other similar material, which panes, in the rear of the characters "Stop" are preferably red in color. The letters "Stop" also have at the outer side of the plate 81 a border 85 surrounding the same which may be formed by a layer of paint, enamel, or thin layer of sheet material. This border is also of the same color as the transparent pane back of the letters and preferably red. At the other opposite sides of said unit, the plates 81 have openings 81a therethrough over which are secured the auxiliary plates 84. These plates have cut therefrom characters 87 adapted to direct traffic to proceed on a thoroughfare and in the embodiment of the invention illustrated these characters are shown as the letters "Go". The letters "Go" are also backed by transparent material such as glass or celluloid, and such material is preferably green in color. The unit shown in Figs. 9, 10, and 12 to 14 is rotatable in standard 40 and a plurality of circumferentially spaced rollers 88 depend from the member 41 being journaled on headed and nutted bolts 89 secured in member 41, which rollers 88 have their outer sides disposed substantially in the circle forming the inner periphery of the member 80 and act as guide means in the rotation of said unit. The member 41 also has secured therein and depending therefrom, rods 90 converging toward their lower ends and 10 having said ends secured to a plate 91. Triangular plate members 92 surround the rods 90 and are held thereby between member 41 and plate 91. A plurality of plates 93 are held between the members 92 and carry electric light sockets 94 in 15 which are disposed the lamp bulbs 95. The members 90 to 94 thus form a light frame which is stationary inside of the rotatable unit shown in Figs. 9 and 10. A socket 96 is secured to the upper side of member 41 by the bolts 97 in which is disposed the lamp bulb 98. The member 43 has small panes of transparent material 99 at the four sides thereof surrounding the lamp 98. The column 40 also has panes of transparent material 100 secured at the inner sides thereof covering 20 the openings 40c. The standard 40 also has a bracket 101 secured to one side thereof carrying a lamp socket 102 in which is disposed the lamp 103 which is in alignment with the openings 40c and panes 100. 30

The timing mechanism or flasher 36 and the connections to the motor 44 and its coils, as well as the connections for the various lamps, are clearly disclosed in Figs. 15, 16 and 17. As there shown, the timing mechanism consists of 35 an insulating drum rotatable in the direction of the arrow on said drum. Said drum has thereon a plurality of conducting segments indicated 36c, 36d, 36e, 36f, 36k and 36m, respectively. The segments 36e and 36f are arranged opposite each other, in spaced relation, as best shown in Fig. 16. The segments 36k and 36m are also disposed opposite each other as best shown in Fig. 17, said segments 36k and 36m being somewhat shorter than the segments 36e and 36f. The segments 40 36c and 36d are arranged adjacent each other at the same side of the rotatable insulating drum as disclosed in Fig. 15. A conducting element 36m connects the segment 36c with the segment 36e and a conducting element 36o connects the segment 36d with the segment 36f. Also, a conducting element connects the conducting segment 36k with the conducting segment 36e, and a conducting element connects the segment 36m with the conducting segment 36f. The conducting segments are otherwise independent of each other. A lead wire 44d extends from a source of power to a brush 36i and arranged to wipe the segments 36e and 36f, and a lead wire 44c extends from said source of power to a brush 36h also arranged to wipe said segments 36e and 36f and disposed opposite the brush 36i. A lead wire 44b extends between the field winding of 44m the motor 44 and a brush 36b arranged to wipe the segment 36d, and a lead wire 44a extends between said field winding and a brush 36a arranged to wipe the segment 36c, the brushes 36a and 36b being disposed opposite each other. The lamps 95 and 98 are connected in parallel across the lead wires 44c and 44d to be permanently lighted, as will be evident. A short lead wire connects the lamp 103 to the lead wire 44c, and a lead wire 44f connects said lamp to a brush 36j arranged to wipe the segments 36k and 36m and disposed opposite 50 55 60 65 70 75

the brush 36*h* and adjacent the brush 36*i*. A conductor 44*g* extends from the battery 44*b* or other source of power to the brush 44*i* and a conductor 44*j* extends from the other brush 44*k* to the battery 44*h* or other source of power. Brushes 44*i* and 44*k* supply current for the armature circuit. The manner in which the timing mechanism operates will be apparent. When the brush 36*i* is engaging the segment 36*f* the motor will be rotated in one direction, the motor field circuit being traced from one side of the source of power 44*b* through the lead wire 44*d*, brush 36*i*, segment 36*f*, the conducting element 36*o* between segment 36*f* and segment 36*d*, segment 36*d*, brush 36*b* and lead wire 44*b* to field winding 44*m*, and thence through lead wire 44*a*, brush 36*a*, segment 36*c*, the conducting element 36*n* between segment 36*c* and segment 36*e*, segment 36*e*, brush 36*h* and lead wire 44*c* back to the other side of the source of power. When the brush 36*i* is engaging the segment 36*e* the motor will be rotated in direction opposite the direction before mentioned, the motor circuit being traced in reverse direction from the source of power 44*h* through said lead wire 44*c*, brush 36*h*, segment 36*f*, the conducting element 36*o* between segment 36*f* and 36*d*, segment 36*d*, lead wire 44*b*, field winding 44*m*, lead wire 44*a*, brush 36*a*, segment 36*c*, the conducting element 36*n*, between segment 36*c* and 36*e*, segment 36*e* which is now under brush 36*i*, brush 36*i* and lead wire 44*d* to the battery or source of power 44*h*. The current thus passes through the field winding 44*m* in a direction opposite to that previously set forth.

35 The segments 36*k* and 36*m* are arranged to be alternately engaged by the brush 36*j* only at or near the time the motor is being reversed. When the brush 36*j* is engaging the segment 36*k* the closed circuit for the lamp 103 is traced from the source through lead wire 44*d*, brush 36*i*, segment 36*e*, the conducting element between segment 36*e* and segment 36*k*, segment 36*k*, brush 36*j*, lead wire 44*f* to the lamp 103, and thence through lead wire 44*c* back to the source. When the brush 36*j* is engaging the segment 36*m* the circuit for lamp 103 is through lead wire 44*d*, brush 36*i*, segment 36*f*, the conducting element between segment 36*f* and segment 36*m*, segment 36*m*, brush 36*j*, lead wire 44*f*, lamp 103, and lead wire 44*c*. The above mechanism for reversing the motor or timing mechanism is merely diagrammatic and it will be understood that other forms of timing mechanism may be used. The invention is not directed to any particular timing mechanism.

60 In operation the signal will be suitably placed at the intersection of two or more thoroughfares and the signal is preferably placed adjacent the center of the intersection where it can be readily seen. The standard is so mounted and constructed that should it be struck by a vehicle such as an automobile, it will not be damaged and will not damage said vehicle. The standard will swing downwardly, the ball 24 rotating on its supporting members 23*a* and pulling on the cable 25 which will flex the springs 27 and 31. After the vehicle has moved over or passed the standard, or the pressure is relieved on the standard, the same will be brought to its normal position by the springs 27 and 31 pulling on the cable 25. The timer 36 will be connected to some suitable source of current and electrical current will be furnished to operate motor 44 and to illuminate the lamps 94, 98 and 103. The motor 44 is reversed at regular intervals by the timing mechanism 36. When the motor turns in one direction it revolves shaft 47 and operating through the clutch comprising the members 51, it turns member 58 which is secured to shaft 60. Shaft 60 is thus rotated and in turn rotates the pinion 65. Pinion 65 rotates the gears 66 and these move around the orbit gears 69 thus turning the bar 67. The said bar continues to turn until one end thereof strikes one of the stop bolts 70*b* when the arm is brought to a stop.

65 When bar 67 strikes one of the stop bolts 70*b*, said bar and shaft 60 are stopped. The motor 44 is thus stopped or braked. The motor, however, rotates a short distance and the clutch comprising the plates 51 slips to permit this extra movement of the motor. The motor is thus not brought to a sudden stop and the motor thus does not always stop in the same position. After the short extra movement, however, the motor is stopped and held stopped and the current is continuously supplied to the motor so that the same exerts a torque on the shafts 44*a*, 47 and 60. The signal unit shown in Figs. 9 and 10 is thus held in one position with its flat sides 25 in alignment with the flat sides of the standard, so that the characters on said units are displayed at the sides of the standard. When the shaft 60 was turned, the yoke 62 was also turned, owing to the fact that it is connected to the flat 30 side of shaft 60 and spring 64 was wound up or flexed in one direction, one end of said spring being moved by the side of said yoke and the other end held by the pin 61*a*. After the signal has been turned to the position described and held there for a desired length of time, the timer 36 will operate to reverse the current through conductors 34 to the motor 44 so that said motor now revolves in an opposite direction. When the motor starts to turn, the spring 64 also 40 unwinds or returns to normal position and this spring exerts a turning impulse on the shaft 60. This gives a start or an initial movement to the signal unit shown in Figs. 9 and 10 and to the shaft 60. The motor, as well as shafts 44*a*, 47 45 and 60 and bar 67, are again rotated in the reverse direction until it again strikes the other stop bolt 70*b*. The bar is thus stopped and the signal unit shown in Figs. 9 and 10 is again stopped with its sides in alignment with the 50 sides of the standard, except that the word "Stop" is now aligned with the side with which the word "Go" was previously aligned. The motor is thus again braked and revolves a short distance owing to the slipping of the clutch comprising 55 disks 51 and is then brought to a stop. The current still flows to the motor and the motor still exerts a torque on the parts as previously described. The spring 64 is wound in the opposite direction and is in position again to exert a 60 starting movement on the parts when the motor is again reversed. The signal unit comprising parts 80, to 86 which is shown in Figs. 9, 10 and 12 to 14, is thus periodically rotated in reverse directions through substantially 90°. The corners of said signal unit, which corners are formed by plates 81, pass into openings 40*b* when the said unit is oscillated. The lamps 95 are continuously lighted and it is unnecessary to periodically light and extinguish the lights in the 70 operation of the signal. The signal is perfectly visible in daylight without the lamps 95, as the characters forming the word "Stop" are colored red, and the characters forming the word "Go" are colored green. The border 85 about the 75

stencil opening 86 in the word "Stop" also accentuates the visibility of the characters and even in a very poor light the signal is quite distinguishable.

- 5 Lamp 93 at the top of the signal is also continuously illuminated and continuously shows a red light through the transparent panes 93 which, as stated, are preferably red. The lamp 103 is periodically illuminated by the timer 36 just before the motor 44 is reversed and then extinguished just as the motor is reversed. This lamp, therefore, constitutes a traffic change signal and indicates that the signal is about to change.
- 15 The spring 64 is so placed that when the current is off the motor 44, the spring will turn the signal unit shown in Figs. 9 and 10 so that the sides are out of alignment with the sides of the standard 49 or so that the sides of said unit or 20 the central line of said sides are aligned with the bisector of the angle at the corners of the standard. When the signal is thus not being operated, neither the "Stop" nor the "Go" sign will be displayed and traffic can proceed on the streets or 25 thoroughfares of the intersection without being controlled. There will thus be no confusion or congestion if for any reason the signal should cease to operate.

From the above description it is seen that applicant has provided a very efficient traffic controlling and directing signal. The device is absolutely non-glare in operation and the signals can be plainly and distinctly seen at all times no matter how the sun is shining on the signal. 35 Only one set of characters are used at each side of the signal so there is no chance for more than one set of characters to be displayed. All of the operating mechanism except the electrically controlled timing device are carried in the standard, 40 and as stated, the standard can be struck by a vehicle without damage. The present signal also requires fewer lamps than the signal disclosed in applicant's previously filed application and the signal is operated with much less expense. The 45 signal is now in operation in many places.

It will, of course, be understood that various changes may be made in the form, details, arrangement and proportions of the parts, without departing from the scope of applicant's invention, 50 which, generally stated, consists in a device capable of carrying out the objects above set forth, in the novel parts and combinations of parts disclosed and defined in the appended claims.

55 What is claimed is:—

1. A traffic signal adapted to be disposed at the intersection of two or more thoroughfares having in combination, a turnable signal unit having opposite sides with characters thereon adapted to be displayed in alignment with said thoroughfares for simultaneously directing traffic to proceed on one thoroughfare and to stop on another, a motor, driving means connecting said motor and unit including a slipping clutch, a spring disposed between said clutch and unit and adapted to be placed under stress when said unit is turned by said motor and driving means, and stop means for limiting the rotating movement of said unit whereby said motor may rotate after said unit is stopped and means for reversing said motor at regular intervals whereby said spring will exert an initial rotating movement on said unit.
2. A traffic signal adapted to be disposed at the 75 intersection of two or more thoroughfares hav-

ing in combination, an elongated hollow standard of comparatively small transverse dimension and substantially square and uniform in horizontal cross section, said standard having openings in its sides at its upper portion, a turnable hollow member centrally mounted in said standard and having opposite faces adapted to be arranged in alignment with and be visible through the openings in said standard, said faces having characters thereon adapted to simultaneously direct traffic to proceed on one thoroughfare and to stop traffic on another, illuminating means projecting into said member, supporting means secured to the bottom of said member and extending downwardly therefrom in said standard, a motor mounted in said standard below said member and having an armature shaft projecting upwardly in axial alignment with said member, means disposed without said standard for periodically reversing said motor, gear means connecting said armature shaft and said downwardly extending means, and stops for said member whereby said member is turned 90 degrees with each reversal of said motor.

3. A traffic signal adapted to be disposed at the intersection of two or more thoroughfares having in combination, an elongated standard of comparatively small transverse dimension having pairs of opposite sides and having openings in said sides at its upper portion, an oscillatable signal member mounted within said standard about an axis extending longitudinally of said standard and having opposite faces visible through said openings with characters thereon for directing traffic to proceed on one thoroughfare and to restrain traffic on another, a rotatable block mounted in said standard below said signal member and axially aligned therewith, laterally spaced gears carried by said block, a gear disposed co-axially with said block and signal member disposed between and meshing with said gears, an annular gear secured to said standard with which said first mentioned gears also mesh, a shaft secured to said second mentioned gear and extending downwardly into said standard, said signal member being connected to said block, and a rotatable motor mounted within said standard having its armature shaft axially aligned with and connected to said last mentioned shaft.

4. A traffic signal adapted to be disposed at the intersection of thoroughfares having in combination, a turnable member having opposite sides adapted to align with said thoroughfares, said sides of said member having traffic directing characters thereon, an electric motor for turning said member, connecting means between said motor and said member, stopping means for limiting movement of said member to align said sides with said thoroughfares, and slipping means constituted as a part of said connecting means, said slipping means being adapted to first brake the movement of said motor upon the operation of said stopping means and to immediately thereafter gradually bring said motor to a dead stop while a torque is yet exerted by said motor upon said connecting means.

5. A traffic signal adapted to be disposed at the intersection of thoroughfares having in combination, a standard having sides aligning with said thoroughfares and openings through said sides, a turnable member having sides adapted to lie adjacent said openings to align with said thoroughfares, said sides of said member having traffic directing characters thereon, an electric motor for turning said member, connecting means be-

tween said motor and said member, stopping means for limiting movement of said member to align said sides of the member with said thoroughfares, and slipping means constituted as a part of said connecting means, said slipping means being adapted to first brake the movement of said motor upon the operation of said stopping means and to immediately thereafter gradually bring said motor to a dead stop while a torque is yet exerted by said motor upon said connecting means.

6. A signal for directing traffic on a thoroughfare, having in combination, a casing, a sign having a traffic directing legend thereon turnable to positions to restrain traffic and direct traffic to proceed on said thoroughfare and to an intermediate position where traffic is neither restrained or

directed to proceed by said signal, a shaft in said casing, means connecting said sign to said shaft, electrically actuated means for turning said shaft and sign alternately and periodically to said positions to restrain and to direct traffic to proceed, respectively, mechanically operated means for turning said shaft and sign to an intermediate position upon the failure of said electrically actuated means, a reduction gearing connection between said shaft and both of said means, and stop members for limiting turning movement of said sign in opposite directions so that said sign is turned substantially 90 degrees between said position to restrain traffic and said position to protect traffic.

FRANK W. GRISWOLD.
